THOMAS BRADY, OF EAST ORANGE, NEW JERSEY.

GAME.

Application filed May 5, 1926. Serial No. 108,834.

This invention relates to games, and particularly to a baseball game.

Various forms of baseball games have been devised but most of such games are 5 more or less complicated and depend for their success in playing on the skill of the players.

This invention has for its object to provide a baseball game that is simple in construction and can be played with equal facility by skilled and unskilled players or, in other words, a baseball game in which success depends on chance rather than skill.

Further objects of the invention will appear from the following specification taken in connection with the drawings, which form a part of this application, and in which

Fig. 1 is a top plan view of a game embodying the invention;

Fig. 2 is a sectional elevation taken substantially on line 2—2 of Fig. 1; and

Fig. 3 is a sectional elevation similar to Fig. 2, but showing the game board constructed of sheet material, such as sheet metal.

The game, briefly described, is played on a game board having a playing field for determining the performance of the players 30 and a diamond for locating the players according to their performance.

The players are represented by marbles or small balls. A portion of the playing field is indicated as the "home plate" and the 35 marble or ball representing the player is placed in this position in a depression by means of which it is maintained at rest. A slight push or shove on the marble will start it rolling through a groove or elongated 40 guideway by means of which it is guided to the field. Since the groove or guideway is straight and is disposed substantially in alinement with the center of the field, it is impossible to change the direction of movement of the ball as it moves to the field.

The field has formed therein a plurality of depressions or openings into one of which the marble or ball may roll. These depressions are indicated or labelled as "1 Base 50 hit", "2 Base hit", "3 Base hit" or "Home run". The field has projections extending inwardly therein from the edge for deflecting the ball. If the ball does not roll into any of the depressions or openings, the player represented by the ball is "out". If, however, the ball rolls into one of the de-

pressions, for instance, into one of those labelled "3 Base hit", the ball is placed on the diamond at the left of the board on "3rd Base".

Three depressions are disposed on the section of the board having a playing field thereon and are labelled "1-Out", "2-Out" and "3-Out".

The other section of the board having a 65 diamond also has a pair of elongated depressions for receiving the marbles representing the two teams, these being adapted to accommodate nine marbles each. Beneath the diamond are a plurality of aligned 70 openings labelled "Runs" in which the marbles completing the circuit or making runs are disposed. This portion of the board also has clips for securing score sheets thereon.

Further details of the invention will appear from the following description.

In the particular embodiment of the invention illustrated, the game board is divided into two sections A and B. The board 80 may be formed of any suitable material, such as wood, pasteboard, papier mâché or sheet metal, and preferably has a raised border 10 formed thereon.

The playing field, as illustrated, is located in the section A and has a raised substantially circular border 11 and a plurality of raised inwardly extending projections 12 angular in outline. The playing field has formed therein a plurality of depressions 13. 90 If the board is formed of sheet metal, these depressions will probably be punched through the metal. These depressions as shown are labelled "1 Base hit", "2 Base hit", "3 Base hit" and "Home run".

The playing field has extending laterally from the edge thereof an elongated runway or guiding slot 15 which terminates in an annular depression 16 labelled "Home plate, batter up". It will be noted that the runway or slot 15 extends substantially diametrically of the playing field.

The section A of the board also has three openings 18, 19 and 20 labelled respectively "1-Out", "2-Out", and "3-Out" and the playing rules are preferably printed at the two sides of the runway 15 so that the players can refer thereto easily and conveniently.

The section B of the board has a diamond 20 formed thereon and provided with depressions 21 labelled "Home", "1st Base", "2nd Base", "3rd Base". At each side of

the diamond there is disposed an elongated depression or slot 25 representing the bench for holding the nine players of each team.

Beneath the diamond there are two sets of 5 alined openings or depressions 30 and 31, each of these sets being labelled "Runs". At the bottom of section B are clips 34 and 35 adapted to hold a score pad 36.

The game is played as follows. One of 10 the marbles or balls representing the players will be taken from the bench and placed in the depression 16. A tap of the finger will cause this ball to roll through the runway or slot 15 onto the playing field. The ball 15 will then roll on the playing field and will either drop into one of the slots or openings or come to rest on the field. If it drops into one of the openings as, for instance, in an opening labelled "2 Base hit", the ball will 20 be removed from the playing field and placed at "2nd base" on the diamond. If, however, the ball comes to rest on the playing field, it will be placed in the opening or depression 18 labelled "1-Out". The second 25 ball will then be placed in the depression 16 and the operation will be repeated and the person playing will continue until there are "three out". Then the person representing the other side of the contest will play in 30 a similar manner. As runs are made, the balls representing the players making the runs will be placed in the depressions 30 or 31 and the score will be kept in the usual manner.

From the foregoing description it will be 35 seen that a simple and practical game has been designed and that success in playing the game depends entirely on chance and not on skill, due to the fact that the balls cannot be projected in any desired direction 40 onto the field but must all enter the field through the groove 15. The borders of this groove are labelled "Foul line" and if a ball leaves the groove over the border, this constitutes a foul and the player can replace 45 the ball and try again.

Although one specific embodiment of the invention has been particularly shown and described, it will be understood that the invention is capable of modification and that 50 changes in the construction and in the arrangement of the various cooperating parts may be made without departing from the spirit or scope of the invention, as expressed in the following claims.

55 What I claim is:

1. A game board having a playing field,

a raised border around said field, depressions scattered in said field and an elongated substantially straight runway leading to 60 said field and alined with the center thereof, said runway having an enlargement at the end thereof remote from the field adapted to support a spherical member, and penalty spaces adjoining said runway. 65

2. A game board having a playing field, a raised border around said field, depressions scattered promiscously in said field and an elongated straight depression leading to said field and alined with the center 70 thereof. 75

3. A game board having a playing field, a raised border around said field, depressions scattered in said field, an elongated runway leading to said field, and deflecting means 75 extending into the field from the border and adapted to deflect a ball. 80

4. A game board having a substantially circular playing field, a raised border around said field, depressions scattered promiscuously in said field and an elongated, straight runway leading to said field, said runway being alined with a diameter of said field, penalty spaces along said runway and deflecting means extending into said field 85 and adapted to deflect a ball. 90

5. A baseball game having a substantially level playing field, a raised border around said field, depressions scattered in said field and an elongated substantially level runway leading to said field, each of said depressions being labelled to indicate a hit or run, penalty spaces along said runway, each space being labelled to indicate a foul line. 90

6. A baseball game board having a playing field thereon provided with a plurality of openings in the surface thereof, each opening being labelled to indicate a base hit or a run, a runway leading to said field, spaces along said runway being labelled to 100 indicate a foul line and a diamond separate from said field and having depressions representing first base, second base and third base. 105

7. A baseball game board having a substantially level playing field, a border surrounding the field, a plurality of openings in the field surface and a depressed runway leading to said field, said runway being bounded by foul lines. 110

In witness whereof, I have hereunto set my hand this third day of May, 1926.

THOMAS BRADY.
